CLAIM

The ornamental design for an electronic device or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of an electronic device or portion thereof with graphical user interface showing our new design; and,

FIG. 2 is a front view of another embodiment thereof.

The peripheral dashed broken lines depict a display screen or portion thereof, and form no part of the claimed design. The dotted broken lines depict boundaries of the claimed design and form no part thereof. The portion of the graphical user interface between the dotted broken lines and the peripheral dashed broken lines that is illustrated in faded gray forms no part of the claimed design.
